TICKET ISSUING MACHINE

Norman E. Bowden and Kenneth O. Bundy,
Dallas, Tex.

Application July 12, 1945, Serial No. 604,662

3 Claims. (Cl. 164—49)

1

This invention relates to ticket issuing machines and more particularly to machines in which the issuing mechanism is controlled by coins or tokens.

The principal object of the invention is to provide a coin actuated mechanism designed and arranged to detach tickets or coupons singly or in multiples from a roll of such tickets or coupons, on which latter is printed certain indicia such as the stipulations and conditions of a traveler's insurance policy; the rules of games of amusement, or other text, depending upon the service which the machine is adapted to perform.

Another object of the invention is to provide a novel form of feeding mechanism for tape, eventually to become tickets, coupons or receipts, combined with cooperating means effective to sever the tape at predetermined points to define the said tickets, coupons or receipts, said mechanism being positive in its action and, by virtue of its simplicity of construction and operation, its performance is highly effective.

With the foregoing objects as paramount, the invention has further reference to certain features of accomplishment which will become apparent as the description proceeds, taken in connection with the accompanying drawings wherein:

Figure 1 is a perspective view of a cabinet, partly broken away, showing a ticket issuing mechanism embodying the invention, and

Figure 2 is a side elevational view, with parts removed to show the coin actuating elements of the mechanism.

Figure 3 is a fragmentary view of the ticket detaching means and associated parts in displaced positions.

Continuing with a more detailed description of the drawing, reference is primarily made to Figure 1 wherein numeral 10 denotes a cabinet which may be of any desired or appropriate design. Arranged in the cabinet is a spindle 11 on which is rotatably mounted a reel 12, carrying a roll of tape 13. If the machine is designed to issue tickets such as may be employed as policies for travel insurance, the tape is perforated transversely at *a*, so that when subsequently cut on each side of the perforation, duplicate tickets are delivered to the operator. These are separated, one being deposited in the machine or in a separate receptacle and the other retained for identification upon comparison with the companion section of the ticket which bears identical markings including duplicate numbers. Other such identifying media such as finger

2

prints, etc. may likewise be employed if desired, to insure against fraud or deception.

The tape 13 is further provided with equidistantly spaced apertures *b* which receive successively protuberances 14, spaced circumferentially about a roller 15. The tape first passes from the reel 12 under a guide roller 16, thence over the roller 15 and is advanced by the pins or protuberances 14 into a guide member 17, wholly enclosing the tape from a point on the feeding roller 15 to the vertically reciprocable blade 18 at the discharge opening at the front of the cabinet 10.

To actuate the described mechanism a hand operated lever 19 has a shaft 20 arranged at its lower end at right angles to the longitudinal axis thereof, which is journaled in a bearing 21, supported on the cabinet floor and a thrust bearing 22 on the opposite wall of the cabinet. Mounted on the shaft 20 is an arm 23, to the free end of which is secured an end of a spring 24, the opposite end of the spring being anchored by means of a pin 25 to the floor of the cabinet. Operation of the various elements to be presently described is effected during return of the lever 19 after it has been pulled forwardly, hence the spring 24 which accomplishes return of the lever, also is responsible for bringing about the operation of said elements, as will be determined later.

An elongated arm 26 is pivoted at 27 to a wall of the cabinet, or other support, and a link 28, pivoted to its forward end at 29, serves to connect the arm to a block 30, carrying a blade 18, operating in relation to an anvil 32 to sever the tape 13 passed therebetween. The block 30 is supported pivotally by links 33, on each side thereof and these links, in turn, are pivoted through a shaft 34 to supporting brackets 35, affixed to and rising from the cabinet floor. To each end of the blade 18 is affixed an end of a spring 36, the opposite end of each spring being connected to a bracket 35.

It is apparent from the foregoing that when the forward end of the elongated arm 26 is depressed, in a manner to be explained presently, the blade 18 will be thrust downwardly by reason of its connection with the arm through link 28. This action is effected against the resistance of springs 36, as well as a spring 37, which is connected at one end to the arm and at the other end to the wall of the cabinet. Thus, the blade 18, after cutting the tape 13, is returned to its original position.

To actuate the arm 26 in the manner described,

3

and arm 38 is affixed to shaft 20 to which the operating handle 19 is attached. The arm 38 carries a roller 39. As the lever 19 is pulled forwardly, the upper end of arm 38 bears against a dog 40, pivoted at 41 to the end of the elongated arm 26, causing the dog to trip upwardly on its pivot, allowing the arm 38 to pass thereunder, after which the dog resumes the position shown in Figure 1. When the lever 19 is released to the action of spring 24, the roller 39, carried by the arm 38, bears against the inclined surface *c* of the dog, causing the arm 26 to rock on its pivot 27, thereby lowering its forward end, with the result earlier described, i. e., actuating the blade 18 to sever the tape 13.

Referring now to the coin mechanism, which, as a careful examination of the drawing will reveal, is effective to advance the tape 13 a distance at the severing point, equal to the spacing between pins 14 on the feeding roller 15.

A coin 41a dropped into the slot 42 will fall down chute 43 and will be intercepted by the deflector 44, disposed in a small housing or receptacle 45, with which chute 43 communicates, as shown. A slidable bar 46, guided by brackets 47, enters the receptacle 45 and its inner end is also engaged by a coin reposing in the receptacle. On the opposite side of the receptacle, a dog 48, having a shank 49 is movable against the coin 41a to urge the bar 46 longitudinally outward through the medium of the coin, which latter serves as the connecting means between the dog and the said bar 46. The results of this action will be explained presently.

It has been stated that the forward movement of the operating lever 19 is ineffective to actuate lever 26 and consequently the blade 18. However, such forward movement does extend the tape in the manner described by actuating arm 38, mounted on the operating shaft 20, and which has a slot 50 intermediate its ends into which extends a pin 51, protruding outwardly from the shank 49 of the dog 48. It is apparent therefore that when lever 19 is pulled forwardly, arm 38 will be similarly actuated, to urge the dog 48 inwardly of the coin receptacle 45, by reason of its connection therewith through pin 51. Thus, pressure of dog 48 on the coin 41a will be transferred to bar 46 and when the coin is moved over the lower section 52 of the coin chute, it will fall thereto when pressure thereon is relieved by releasing the operating lever 19, being directed in this course by deflector 44.

In the course of the foregoing operation, an arm 53, pivoted at 54 to the bar 46 and further pivoted at 55 intermediate its ends to the casing wall, actuates an elongated bar 56, lying alongside the said casing wall and supported thereon by brackets 57. The said arm 53 is slotted at 58 to receive a pin 59 affixed to and extending outwardly from the bar 56. Thus, when the coin actuated bar 46 is moved to the left in Figure 2, bar 56 is moved in a counter direction through the pivoted arm 55.

As the bar 56 is moved as explained, it causes the feeding roll 15 to revolve a limited amount through an arm 60 and a dog 61, mounted on its upper end and cooperating with a ratchet wheel 62, mounted on the shaft 63 of the feeding roll 15. It is pointed out that the arm 60 is free to oscillate on the roller shaft 63 and by virtue of a slot 64 at its lower end, engageable with a pin 65 on the bar 56, the arm is moved to and fro thereby and in so moving, the dog

4

61 renews its position in relation to the teeth on the ratchet wheel 62, affixed to the feeding roller 15, thereby rotating the latter a distance predetermined by the spacing of the teeth of the ratchet wheel, which spacing corresponds to that of the tape moving pins 14 disposed circumferentially about the roller 15.

At the forward end of the ratchet actuating bar 56 is attached a spring 66, through a link 67, and which spring is in turn attached to one of the brackets 35, previously mentioned. This spring serves to return the bar 56 to its original position when displaced as described.

Reviewing the operation of the ticket issuing machine; when a coin is dropped into chute 43, it comes to rest in the receptacle 45, in which position it renders the connection between dog 48 and bar 46 rigid so that upon forward movement of lever 19, the bar 46 will be similarly moved to actuate the dog 61 through arm 53, bar 56 and arm 60, to advance the tape a predetermined distance at the front of the casing 10. It has been explained that forward movement of lever 19 has no effect to cut the tape, due to the pivoted member 40 at the end of the blade actuating arm 26, which yields to the arm 38 in its forward movement. However, when the operating lever 19 is released to the action of spring 24, the roller 39 carried by the arm 38 will move against the deflecting surface *c* of the member 40, exerting a force upward on the end of arm 26, causing the opposite end to move downwardly, advancing the blade 18 onto the tape. The action is sudden, due to the spring 24 and the tape is quickly and cleanly cut, especially in view of the peculiar V-shape of the cutting edge *d* of the blade 31.

Manifestly, the construction as shown and described is capable of some modification and such modification as may be construed to fall within the scope and meaning of the appended claims is also considered to be within the spirit and intent of the invention.

What is claimed is:

1. A ticket issuing machine including a cabinet having a slotted opening in its forward end through which printed perforated tape is discharged, a reel in said casing carrying a roll of said tape, a guide roller and a feeding roller under and over which said tape is moved respectively from said reel, said feeding roller having radially extending pins spaced circumferentially on its periphery adapted to successively enter the perforations in said tape, means to effect intermittent rotation of said roller for apportioning tape from said reel, tape cutting means adjacent the slotted opening of said cabinet, an actuating arm therefor, coin controlled means for actuating said tape apportioning means, a lever manually operable in one direction and automatically operated in a reverse direction to respectively actuate said tape apportioning means and said tape cutting means.

2. A ticket and coupon issuing machine including a casing, a roll of printed tape in said casing having longitudinally spaced perforations therein, a guide roller and a feeding roller having radial pins spaced circumferentially on its periphery successively entering the perforations in said tape for advancing said tape to a point of discharge from said casing, a tape apportioning means for intermittently rotating said feed roller, tape cutting means adjacent to and movable vertically across said discharge point, means controlled by the presence of a coin for actuat-

ing said apportioning means, an operating lever, means effective upon forward movement of said lever for actuating said coin controlled means and upon reverse movement thereof for actuating said tape cutting means.

3. In a machine of the character described, a roll of printed tape, guiding and feeding means for said tape consisting of a roller having circumferentially spaced pins intermediate its ends entering apertures at spaced distances in the tape and further having a ratchet wheel at one end thereof, an arm pivoted intermediate its ends, carrying a dog engageable with the teeth of said ratchet wheel, a longitudinally movable bar for oscillating said pivoted arm, cutting means disposed forwardly of said feeding means, means for predetermining the quantity of tape fed from said feeding means and means for ac-

tuating said predetermining means upon movement in one direction and for actuating said cutting means upon movement in the opposite direction.
